CLAIM

The ornamental design for a suntanning pool, as shown and described.

DESCRIPTION

FIG. 1 is a perspective view of a suntanning pool showing my new design;

FIG. 2 is a top plan view thereof;

FIG. 3 is a bottom plan view thereof;

FIG. 4 is a side elevational view thereof;

FIG. 5 is an elevational view thereof taken from the side opposite that shown in FIG. 4;

FIG. 6 is an end elevational view thereof; and,

FIG. 7 is an elevational view thereof, taken from the end opposite that shown in FIG. 6.

FIG. 1

FIG. 2

FIG. 3

FIG. 4

FIG. 5

FIG. 6

FIG. 7
